US0D1113315S

(12) United States Design Patent (10) Patent No.: US D1,113,315 S
(45) Date of Patent: * Feb. 17, 2026

(54) PORTABLE WATER PURIFIER

(71) Applicant: Good uija Intelligent Technology (Luoyang) Co., Ltd., Suzhou (CN)

(72) Inventor: Guodong Song, Lishui (CN)

(73) Assignee: Good uija Intelligent Technology(Luoyang) Co., Ltd., Suzhou (CN)

() Term: 15 Years

(21) Appl. No.: 29/967,650

(22) Filed: Oct. 11, 2024

(51) LOC (15) Cl. 07-01

(52) U.S. Cl.

USPC D7/311; D23/207

(58) Field of Classification Search

USPC D23/207, 208, 209, 210; D7/306, 309,

(57) CLAIM

The ornamental design for a portable water purifier, as shown and described.

DESCRIPTION

FIG. 1 is a front, right and top perspective view of a portable water purifier, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the portable water purifier that form no part of the claimed design.
